Peter Schladermundt, Bronxville, N. Y., and Warren B. Green, Darien, Conn., assignors to Sears, Roebuck and Co., Chicago, Ill., a corporation of New York

Application September 19, 1946, Serial No. 133,418

Term of patent 14 years

(Cl. D4—4)

To all whom it may concern:

Be it known that we, Peter Schladermundt and Warren B. Green, citizens of the United States, and residents respectively of 8 Park Avenue, Bronxville, in the county of Westchester and State of New York, and 37 Christy Hill Road, Darien, Fairfield County, Connecticut, have invented a new, original, and ornamental Design for a Bathtub, of which the following is a specification, reference being had to the accompanying drawing, forming a part thereof.

Fig. 1 is a plan view of the bathtub showing our new design; and

Fig. 2 is a perspective view of the tub featured in Fig. 1, showing our new design.

We claim:

The ornamental design for a bathtub, as shown and described.

PETER SCHLADERMUNDT,
WARREN B. GREEN.
